UNITED STATES PATENT OFFICE.

GEORGE H. CHENEY, OF ROCHESTER, NEW YORK.

DESIGN FOR A BICYCLE-HUB.

SPECIFICATION forming part of Design No. 33,383, dated October 16, 1900.

Application filed September 14, 1900. Serial No. 30,075. Term of patent 7 years.

To all whom it may concern:

Be it known that I, GEORGE H. CHENEY, a citizen of the United States, and a resident of Rochester, in the county of Monroe and State of New York, have invented and produced a certain new and original Design for Bicycle-Hubs, of which the following is a specification.

Figure 1 is a side elevation of the hub, showing my new design; and Fig. 2 is a sectional view taken on the line 2 2 of Fig. 1.

As shown in the drawings, the leading or material feature of my design consists of the two similar truncated cones A and B, whose tops are adjacent to each other, the cylindrical portions C and D adjacent to the base of said cones A and B, respectively, the

flanges E and F adjacent to the other ends of the cylindrical portions C and D, respectively, and the cylindrical portion G adjacent to and outside of said flange F.

It is apparent that the design is also applicable to hubs for other vehicles besides bicycles.

Having described my invention, what I claim as new, and desire to secure by Letters Patent, is—

The design for a hub as herein shown and described.

GEORGE H. CHENEY.
